UNITED STATES PATENT OFFICE.

HERMAN WESTLING, OF HUDSON, MASSACHUSETTS, ASSIGNOR TO APSLEY RUBBER COMPANY, OF HUDSON, MASSACHUSETTS, A CORPORATION OF MASSACHUSETTS.

SHOE.

1,349,745.

Specification of Letters Patent. Patented Aug. 17, 1920.

Application filed November 24, 1919. Serial No. 340,166.

To all whom it may concern:

Be it known that I, HERMAN WESTLING, a citizen of the United States, residing at Hudson, in the county of Middlesex and 5 State of Massachusetts, have invented a certain new and useful Improvement in Shoes, of which the following is a specification, reference being had therein to the accompanying drawings.

10 The invention relates to a new and useful improvement in shoes and the manufacture of same. It has special reference to rubber-soled shoes, and is more particularly intended to be applied to use in the manufacture of canvas-topped shoes, although not necessarily limited to canvas shoes.

In the manufacture of rubber-soled shoes heretofore it has been impracticable to provide a steel shank incorporated into the shoe 20 by reason of the fact that the end of the steel shank has a tendency to cut the rubber sole or cause the sole to crack transversely thereof at the end of the steel shank. The object of the present invention is to provide such a construction that the steel shank 25 is prevented from cutting or causing the breaking of the outer sole.

The invention will be fully understood when taken in connection with the accompanying drawings, and the novel features 30 will be clearly pointed out and defined in the claims at the close of this specification.

In the drawings, Figure 1 is a longitudinal sectional view of the assembled upper 35 and insole mounted on the last, the insole having a sheet of rubberized cloth secured thereto, the rubberized cloth having a transverse slot for the passage of the steel shank.

Fig. 2 is a detail view of the steel shank. 40 Fig. 3 is a sectional view on the same line as Fig. 1, showing the steel shank introduced into position with relation to the insole and rubberized cloth covering.

Fig. 4 is a detail plan view of the leveling 45 member surrounding the steel shank.

Fig. 5 is a sectional view showing the shoe after it has been lasted and the leveling member assembled with the other parts, the outer sole and heel being shown by dotted lines.

Fig. 6 is a bottom plan view of a shoe 50 after the parts are assembled, as shown in Fig. 5, before the outer sole is attached.

Referring now to the drawings, 1 represents the last, 2 the canvas upper and 3 the

inner sole. On the bottom of the inner sole there is cemented a covering 4 of thin flexible material, preferably rubberized cloth, having a rubberized face outside. A slit 5 is formed in the rubberized cloth in 60 a transverse direction of the inner sole, as shown in Figs. 1 and 6, this slit being of a width, to readily admit the insertion of one end of a steel shank 6. The steel shank 6 is formed with a hole 7 near the rear end 65 to form a tack hole. The slit 5 is formed in the rubberized cloth just back of the ball of the shoe. The forward end of the steel shank is inserted through the slit 5 and slipped forward under the rubberized cloth 70 a short distance as shown in Fig. 3. The rubberized cloth can easily be loosened up at that point sufficient to allow the introduction of the steel shank.

The rear end of the steel shank extends 75 backward as usual in the use of steel shanks, preferably extending back somewhat onto the heel portion of the inner sole. The rear end of the shank is held down in position by means of a tack 8 which passes 80 through the hole 7 in the steel shank and is driven into the insole to hold it in position.

At this stage in the construction of the shoe the steel shank is exposed, except that portion at the forward end which is slipped 85 through the slit, and this leaves an overlying lifted up portion of the rubberized cloth forming a slight projection 9 equal to the thickness of the rubberized cloth and extending the length of the overlapped portion of the steel shank. Where the steel shank overlies the rubberized cloth to the rear of the slit, the said steel shank forms a protuberance equal to its own thickness. For that reason I provide a leveling piece to 90 cover that portion of the shank and heel portion of the inner sole which surrounds the steel shank so as to form a more level surface. This leveling member is shown in Fig. 4 and consists of a piece of flexible 95 material, preferably rubberized cloth 10 which may be a little thicker than the rubberized sheet 4, previously referred to as applied to the insole. It should be about the thickness of the steel shank. This leveling member 10 is shaped in contour to fit the heel and shank portion of the insole and to extend some distance forward of the shank portion of the sole up onto the ball.

This leveling member is formed with a slot 110

- 11 of the size and shape of the steel shank 6, so that when the said leveling member is applied to the inner sole the steel shank member will lie within said slot and all other parts will be covered by the leveling member. This will bring the face of the leveling member up to the level of the outer face of the steel shank. If desired the leveling member may be skived down toward the forward end as shown in Fig. 5.
- 10 The outer sole 12 and welt 13 may then be applied and the outer sole stitched to the welt by stitches 14, as shown in Fig. 5, and the shoe is then vulcanized to unite the outer sole and inner sole through the medium of the rubberized intermediate sheet 4 and leveling member 10. By this form of construction the forward end portion of the steel shank is covered by the rubberized cloth 4, and the rear portion of the steel shank extends under the heel, and the leveling member 10 fills up all around the steel shank to produce a level surface for the reception of the outer sole.
- 15 25 What I claim is:—
1. A rubber-soled shoe having an inner sole, a covering layer of thin flexible material on the bottom of the inner sole, said covering layer having a transverse slit therein at the forward part of the shank portion thereof, a metal shank member which extends through said slit, the forward end portion of the metal shank lying between said covering layer and the inner sole, the other portion of said shank member extending rearwardly over the outer face of the shank portion of the inner sole, a leveling member extending from the heel portion forward over the shank portion of the inner sole to a point forward of said metal shank, said leveling member having a slot therein which receives the said metal shank member, and an outer sole for the bottom of the shoe.
  2. A rubber-soled shoe having an inner sole, a covering layer of rubberized cloth on the bottom of the inner sole, said rubberized cloth having a transverse slit therein at the forward part of the shank portion thereof, a metal shank member which extends through said slit, the forward end portion lying between the said rubberized cloth and the inner sole, the greater portion of said shank member extending rearwardly over the outer face of the shank portion of the shoe and fastened at its end to the inner sole, a leveling member composed of rubberized cloth extending over the outer face of the inner sole from the heel portion to a point forward of said metal shank, said leveling member having a recess opening therein which receives the said metal shank member, and a rubber outer sole which covers the said inner sole.

ing layer and the inner sole, the other portion of said shank member extending rearwardly over the outer face of the shank portion of the inner sole, a leveling member extending from the heel portion forward over the shank portion of the inner sole to a point forward of said metal shank, said leveling member having a recess therein which receives the said metal shank member, and an outer sole for the bottom of the shoe.

3. A rubber-soled shoe having an inner sole, a covering layer of rubberized cloth on the bottom of the inner sole, said covering layer having a transverse slit therein at the forward part of the shank portion thereof, a metal shank member which extends through said slit, the forward end portion of the metal shank lying between said covering layer and the inner sole, the other portion of said shank member extending rearwardly over the outer face of the shank portion of the inner sole, a leveling member composed of rubberized cloth extending from the heel portion forward over the shank portion of the inner sole to a point forward in said metal shank, said leveling member having a slot therein which receives the said metal shank member, and a rubber outer sole for the bottom of the shoe.

4. A rubber-soled shoe, having an inner sole, a covering layer of rubberized cloth on the bottom of the inner sole, said rubberized cloth having a transverse slit therein at the forward part of the shank portion thereof, a metal shank member which extends through said slit, the forward end portion lying between the said rubberized cloth and the inner sole, the greater portion of said shank member extending rearwardly over the outer face of the shank portion of the shoe and fastened at its end to the inner sole, a leveling member composed of rubberized cloth extending over the outer face of the inner sole from the heel portion to a point forward of said metal shank, said leveling member having a recess opening therein which receives the said metal shank member, and a rubber outer sole which covers the said inner sole.

In testimony whereof I affix my signature.
HERMAN WESTLING.
